[57] CLAIM

The ornamental design for a faucet spout, as shown.

DESCRIPTION

FIG. 1 is a perspective view taken from the top, front and right side of a faucet spout showing my new design; FIG. 2 is a front elevational view thereof;

FIG. 3 is a right side elevational view thereof, the left side being a mirror image of the right side shown; and FIG. 4 is a top plan view thereof.

The water supply pipe is broken away for convenience of illustration in FIGS. 2 and 3.
